UNITED STATES PATENT OFFICE.

WILLIAM C. YATES, OF SCHENECTADY, NEW YORK, ASSIGNOR TO GENERAL ELECTRIC COMPANY, A CORPORATION OF NEW YORK.

STARTING-RHEOSTAT.

No. 857,142.

Specification of Letters Patent.

Patented June 18, 1907.

Application filed December 1, 1905. Serial No. 289,834.

To all whom it may concern:

Be it known that I, WILLIAM C. YATES, a citizen of the United States, residing at Schenectady, county of Schenectady, State 5 of New York, have invented certain new and useful Improvements in Starting-Rheostats, of which the following is a specification.

This invention relates to devices for controlling electric circuits and has for its object 10 the provision of circuit controlling means whereby the motor may be stopped, started and generally controlled in a reliable, safe and efficient manner.

More particularly, my invention relates to 15 means for controlling motors of a type adapted to be run at a slow speed in addition to the normal running speed, and which it is desirable should be stopped and started quickly when running at reduced speed. This type 20 of control is commonly used in connection with printing presses in which it is desirable that means be provided whereby the press may be "jogged" along at a slow speed from different points around the press. It is, of 25 course, necessary that a certain amount of resistance be in series with the motor when it is being "jogged" along, preferably a portion of the regular starting resistance.

In carrying out my invention, I provide 30 means whereby the press may be "jogged" along at a slow speed with a portion of the starting resistance in series with the motor and the controlling arm in the starting or "off" position. I also provide means for 35 braking the motor after the circuit is opened and for regulating the speed at which the motor is run both in "jogging" and normal running.

My invention therefore consists in the features of construction and arrangement and 40 combination of elements hereinafter set forth and particularly pointed out in the claims annexed to and forming a part of this application.

45 In the drawings, Figure 1 is a plan view of a rheostat embodying my invention; Fig. 2 is a detail of the operating and controlling arms; Fig. 3 is a plan view of the same; Fig. 4 is a diagram of circuits; and Fig. 5 shows the 50 circuit connections of the brake resistance.

I shall first describe the mechanical construction and the arrangements of parts of my device, and then point out the circuit connections and mode of operation.

Referring to the drawings, 1 is the usual 55 insulating base of slate or soapstone having a series of contact segments 2 and 3 forming the terminals of the starting resistance 4. The segments 3 are the reversing segments and are separated from the segments 2 by 60 insulating segments 5 which insulate the conducting segment 6 from the segments 2 and 3. Conducting segments 7 and 8 are likewise mounted upon the base concentric with segments 2 and 3 and are also provided 65 with reversing segments 9 and 10 and conducting segments 11 and 12 insulated respectively from the segments 7 and 10, 8 and 9, and in alinement with the segment 6. The controlling mechanism comprises an operating arm 13 secured to but insulated from the shaft 14 by means of an insulating washer 15 and a controlling arm 16, likewise secured to the shaft and biased to a central position over the contacts 6, 11 and 12 by means of 70 the spring 17 having its ends 18 and 19 engaged by the pins 20 and 21, the former being secured to the movable hub 22 of the controlling arm and the latter fixed in the base 1.

In order to accurately center the controlling arm in the "off" position, I provide an arm 23 pivoted to the base at 24 and provided with a lug or roller 25 engaging a notch 26 in the hub 22, the arm being spring-pressed 85 toward the hub by means of a spring 27 secured to the pin 21. The arm 16 is provided with a contact 28 in conductive relation with the arm and bridging contact 29 insulated therefrom. These contacts are preferably 90 of the laminated type and a carbon contact 30 is provided in connection with contact 29. A no-voltage release magnet 31 of the usual type is provided so as to retain the controlling arm in the running position. 95

For the purpose of regulating the speed of the motor, both in "jogging" and normal running, I provide a regulator having an adjusting knob 32 and a pair of controlling arms 33 and 34 coöperating respectively 100 with contact studs 35 and 36, contact segments 37 and 38 adjoining respectively each of these sets of studs. The regulating arm normally rests between the two sets of studs and with its controlling members in contact 105 with the segments 37 and 38. The studs 35 and 36 form the terminals of the regulating resistances 39 and 40, respectively, the 110

former being in series with the field and the latter in series with the armature so that by moving the controlling arm to the right so as to cut resistance in the field, the motor 5 may be speeded up, while movement to the left cuts resistance into the armature circuit to reduce the speed.

For controlling the motor from a distant point, I provide a relay comprising a solenoid 41 having a core provided with bridging contacts 42 and 43, bridging respectively, the contacts 44, 45, and 46, 47. The circuit of the relay is controlled by a series of switches or push-buttons 48, preferably arranged in parallel, although I do not limit my invention to this particular mode of connection.

The arrangement of circuits and mode of operation of my device are as follows: As before stated, the motor is "jogged" along when the controlling arm is in the "off" or central position. With the arm in this position, the segments 6 and 11 are bridged by contact 29 and the contact 28 is in engagement with segment 12. When now it is desired to "jog" the motor, any one of the buttons 48 is pressed to energize the solenoid 41. This bridges the contacts 44 and 45 to close the motor circuit and also bridges the contacts 46 and 47 to short-circuit the no-voltage release magnet 31, as hereinafter described. With the contacts 44 and 45 bridged, the direction of the current will be as follows: From the line at L to the pivotal point 49 of the regulating arm, thence to segment 38, and by conductor 50 to the pivotal point 51 of controlling arm 16, thence through the arm and contact 28 to segment 12, conductor 52, armature A, conductor 53, segment 7, conductor 54, bridge 42, conductor 55, to segment 2 of the starting resistance, thence through a portion of the starting resistance and conductor 56, back to line at L'. It will be noted that the motor connection is made with one of the intermediate segments 2 so as to include a part of the resistance in series with the motor at starting. This segment may be so located as to include as much of the starting resistance in circuit as is desired, the connection being made however at a fixed point. When it is desired to vary the speed at which the motor is "jogged" along, this may be done by means of the regulator. A resistance R is arranged in parallel with the armature A by being shunted across the armature terminals from segment 12 to segment 10, conductor 57, segment 6, bridge contact 29 to segment 11, resistance R, to segment 7. This resistance R therefore, retards the speed of the motor when "jogging" and also acts as a brake resistance when the motor circuit is opened, as shown in Fig. 5, the motor being short-circuited through this resistance so as to quickly stop it. With the button 48

pressed, the motor will run at a slow speed having in circuit a portion of the starting resistance and the resistance R. When the push-button is released and the solenoid 41 deenergized, the motor circuit is broken at bridge 42 and the motor immediately stops. By this means the motor may be stopped and started very quickly and advanced by small increments. When it is desired to run the motor at normal speed, the controlling arm is moved over the segments 2, the direction of the current being as follows: From the line at L through the regulating arm to segment 38, thence to the controlling arm at 51, through the arm and contact 28 to segment 8, thence through conductor 52, armature A, conductor 53, segment 7, bridge contact 29; through the resistance 4 and conductor 56, back to line at L'. The arm is then moved to the right until it is retained in the running position by the no-voltage magnet 31. The motor now being in a running position and it is desired to stop it, one of the push-buttons 48 is pressed, bridging the contacts 46 and 47, short-circuiting the magnet, which is preferably in series with the field through conductor 58, bridge 43 and conductor 59, the magnet being connected with the line at 49, through conductor 60, and with the line L' and field F through conductors 61 and 56. The arm being released from the no-voltage magnet, it will immediately return to the "off" position, and may then be "jogged" along by means of the buttons, as above described.

When it is desired to reverse the motor, the controlling arm is moved to the left but no provision is made for maintaining the arm in a reversing position, since this is usually unnecessary. The direction of the current when the motor is reversed is as follows: From line L through the regulating arm to arm 16 and contact 28, segment 9, conductor 62, conductor 53, armature A, conductor 52, segment 12, conductor 63, segment 10, thence across bridging contact 29 to segments 3, which are connected with the segments 2 by conductors 64, thence through the starting resistance and conductor 56, back to line.

It will thus be seen that I have provided a simple and efficient means for operating a motor at different speeds and for stopping and starting quickly from remote points, while with my arrangement, it is not necessary to operate the controller arm in order to stop and start from remote points. I also provide means for regulating both in running and in "jogging," and also for reversing the motor in a very safe and efficient manner.

What I claim as new and desire to secure by Letters Patent of the United States, is,—

1. The combination with a motor, of a starting rheostat therefor, and means whereby the motor may be controlled through a portion of the starting resistance with the

controlling arm of the rheostat in the off position.

2. The combination with a motor, of a starting rheostat therefor, and electrically controlled means whereby the motor may be controlled through a portion of the starting resistance with the controlling arm of the rheostat in the off position.

3. The combination with a motor, of a starting rheostat therefor, a plurality of switches, and means whereby the motor may be controlled through a portion of the starting resistance from said switches with the controlling arm of the rheostat in the off position.

4. The combination with a motor, of a starting rheostat therefor, a plurality of switches arranged in multiple, and means whereby the motor may be controlled through a portion of the starting resistance from said switches with the controlling arm of the rheostat in the off position.

5. The combination with a motor, of a starting rheostat therefor, an auxiliary switch, means whereby the motor may be controlled from said switch through a portion of the starting resistance with the controlling arm in the off position, and means whereby the motor may be stopped from said switch when the controlling arm is in the running position.

6. The combination with a motor, of a starting rheostat therefor, a plurality of switches, means whereby the motor may be controlled from said switches through a portion of the starting resistance with the controlling arm in the off position, and means whereby the motor may be stopped from said switches when the controlling arm is in the running position.

7. The combination with a motor, of a starting rheostat therefor, an auxiliary switch, means whereby the motor may be controlled from said switch through a portion of the starting resistance with the controlling arm in the off position, a no-voltage

release magnet, and means controlled by said switch for deenergizing said magnet.

8. The combination with a motor, of a starting rheostat therefor, a plurality of switches, means whereby the motor may be controlled from said switches through a portion of the starting resistance with the controlling arm in the off position, a no-voltage release magnet, and means controlled by said switches for deenergizing said magnet.

9. The combination with a motor, of a starting rheostat therefor, a plurality of switches arranged in multiple, means whereby the motor may be controlled from said switches through a portion of the starting resistance with the controlling arm in the off position, a no-voltage release magnet, and means controlled by said switches for deenergizing said magnet.

10. The combination with a motor, of a starting rheostat therefor, an auxiliary switch, means controlled by said switch whereby the motor may be operated at less than normal running speed, a resistance in the motor circuit, and means whereby said resistance acts as a retarding resistance when the motor is being controlled by the switch and as a brake resistance when the motor circuit is broken.

11. The combination with a motor, of a starting rheostat therefor, a plurality of switches, means whereby the motor may be controlled through a portion of the starting resistance from said switches with the controlling arm of the rheostat in the off position, a resistance in the motor circuit, and connections whereby said resistance acts as a retarding resistance when the motor is being controlled by the switches and as a brake resistance when the motor circuit is broken.

In witness whereof, I have hereunto set my hand this 29th day of November, 1905.

WILLIAM C. YATES.
